UNITED STATES PATENT OFFICE.

ROBERT STOCK, OF SANDUSKY, OHIO.

BOTTLE-CAP.

1,400,918.

Specification of Letters Patent. Patented Dec. 20, 1921.

Application filed February 3, 1920. Serial No. 355,966.

To all whom it may concern:

Be it known that I, ROBERT STOCK, a citizen of the United States, and resident of the city of Sandusky, in the county of Erie and State of Ohio, have invented a new and useful Improvement in Bottle-Caps, of which the following is a specification.

This invention relates to improvements in bottle caps and has for its object to provide a detachable closure for bottles, which is simple and inexpensive to manufacture; which will efficiently seal the neck of a bottle when applied thereto, and which may be applied to and removed from the bottle innumerable without destroying its usefulness.

A practical embodiment of my invention is represented in the accompanying drawing, in which,

Figure 1 represents a plan view of my improved cap as applied to a bottle.

Fig. 2 represents a front elevation of the same.

Fig. 3 represents a plan view with the parts in position to remove the cap.

Fig. 4 represents a front elevation of the same.

Fig. 5 represents a vertical section taken in the plane of the line V—V of Fig. 2, looking in the direction of the arrows.

Fig. 6 represents a detail horizontal section taken through the ring controlling device, with the parts in the position shown in Figs. 1, 2 and 5, and

Fig. 7 represents a similar view with the parts in the position corresponding to Figs. 3 and 4.

The bottle to which my improved cap is applied is provided with an annular bead denoted by 1, formed at the mouth of the bottle, and an annular recess 2, on the neck 3, of the bottle immediately below the bead.

The cap 4 is formed with a depending flange 5, which has a series of fingers 6, arranged to be bent to receive and retain, in position thereon, a resilient ring 7. This ring 7 is developed into arms 8, 9, which extend laterally from between two fingers and parallel to each other. A disk 10 is mounted to rotate upon the arm 8, and has in its face an arcuate slot 11, arranged eccentrically with respect to the arm 8. The arm 9 is held in the slot 11, by means of an enlarged head 12, and moved in the slot toward and away from the arm 8 by the rotation of the disk.

The ring 7 is normally expanded to hold

the fingers a slight distance away from the recess 2, when the cap is placed in position on the bottle, so that as the arm 9 is drawn toward the arm 8 by the slot 11 in the rotatable disk 10, the ring will be contracted, thereby causing the fingers to be pressed inwardly into the recess 2. The interior diameter of the ring and fingers is approximately less than the exterior diameter of the bead 1, on the neck of the bottle, so that as the cap is forced downwardly on the bead 1, the fingers and ring will expand slightly until they pass into the recess 2.

A tight closure is effected between the mouth of the bottle and the cap, by means of a disk shaped washer 13 of cork or other yielding material, which will be pressed tightly over the mouth of the bottle by the contraction of the ring and fingers engaging the lower edge of the bead, as shown in Figs. 2 and 5.

The cap may be removed from the bottle by rotating the disk 10 clockwise, which allows the arm 9 to move to the left in the slot 11, and away from the arm 8, which movement of the arm 9 is actuated by the expansion of the resilient ring 7. This expansion of the ring 7, draws the fingers away from the walls of the recess and with a slight upward pressure on the cap, the fingers and ring will be brought into engagement with the bead and expanded a slight distance to pass over the bead.

The disk 10, in the present form, is cupped, as shown at 14, and may be closed by a plug 15, to conceal the ends of the arms 8, 9.

The disk and arms may also be used as a convenient means by which the cap may be lifted from the bottle.

It is obvious that various changes may be resorted to in the form, construction and arrangement of the parts, without departing from the spirit and scope of my invention; hence I do not intend to be limited to the details herein shown and described, except as they may be included in the claims.

What I claim is:

1. A bottle cap having depending fingers, a resilient ring carried by said fingers developed into arms extending laterally therefrom and parallel to each other, and a disk rotatably fixed on one arm and having a slot for the reception of the other arm, said slot being arranged eccentrically with respect to the pivot, whereby the rotation of said disk

will move the arms toward and away from each other and contract and expand the ring and fingers.

2. A bottle cap having depending fingers, 5 a resilient ring carried by said fingers developed into arms extending laterally therefrom and parallel to each other, a cup-shaped disk rotatably fixed on one arm and having a slot for the reception of the other arm, said slot 10 being arranged eccentrically with respect to

the pivot, whereby the rotation of said disk will move the arms toward and away from each other and contract and expand the ring and fingers, said disk arranged to receive a plug for concealing the slot and pivot. 15

In testimony, that I claim the foregoing as my invention, I have signed my name this 12th day of January, 1920.

ROBERT STOCK.
